END LINK FOR A BRACELET OR SIMILAR ARTICLE

Murray L. Cowan, Norwood, Mass., assignor to Textron,
Inc., Providence, R.I., a corporation of Delaware

Filed July 18, 1969, Ser. No. 18,265

Term of patent 14 years

Int. Cl. D11—01

U.S. Cl. D45—4

FIG. 1

FIG. 2

FIG. 4

FIG. 1 is a top plan view of an end link for a bracelet or similar article showing my new design;

FIG. 2 is a side elevational view;

FIG. 3 is an end elevational view looking from the left of FIG. 1; and

FIG. 4 is a perspective view thereof.

I claim:

The ornamental design for an end link for a bracelet or similar article, substantially as shown.
